DESIGN FOR A HOSE NOZZLE

Thomas F. Slater, Waterbury, Conn., assignor to Scovill Manufacturing Company, Waterbury,
Conn., a corporation of Connecticut

Application September 17, 1937, Serial No. 71,665

Term of patent 14 years

To all whom it may concern:

Be it known that I, Thomas F. Slater, a citizen of the United States, residing at Waterbury, county of New Haven, State of Connecticut, have invented a new, original, and ornamental Design for a Hose Nozzle, of which the following is a specification, reference being had to the accompanying drawing, forming part thereof, and in which,—

The figure is a view in elevation of the hose nozzle embodying my new design.

The design on the opposite side of the nozzle
is identical with that shown in the drawing.

I claim:

The ornamental design for a hose nozzle substantially as shown and described.

THOMAS F. SLATER.
